UNITED STATES PATENT OFFICE.

JOSEPH F. SCHOEPLI, OF BALTIMORE, MARYLAND.

METALLIC-WEAVE CONSTRUCTION FOR BOTTLE-HOLDERS AND OTHER FRAMES.

1,027,358.

Specification of Letters Patent.

Patented May 21, 1912.

Continuation of application Serial No. 509,277, filed July 24, 1909. This application filed May 28, 1910.
Serial No. 563,943.

To all whom it may concern:

Be it known that I, JOSEPH F. SCHOEPLI, a citizen of the United States of America, residing at Baltimore, State of Maryland, have invented certain new and useful Improvements in Metallic-Weave Construction for Bottle-Holders and other Frames, of which the following is a specification, reference being had therein to the accompanying drawing.

This invention relates to improvements in crates, and relates more particularly and specifically to improvements in the bottle holding means employed in shipping crates for maintaining the bottles in the crate in an upright position and spaced relatively to each other, this application being a continuation of my application filed July 24, 1909, Serial No. 509,277.

The invention has for its object to provide metallic bottle holding means of a comparatively light weight, yet of extreme rigidity and strength, so that when placed in the crate it will be capable of withstanding all of the ordinary rough usage to which devices of this character are subjected.

It is further the object of this invention to provide a metal weave construction of comparatively light weight, which confines its separating cells to their assigned size and space and fixes them inflexibly, without the use of solder, rivets or other binding means.

A still further object of the present invention is to provide a bottle holding means which, when mounted within a crate, whether the latter be of a wood or metal construction, is so constructed and arranged that no crevices or grooves remain in the crate for the accumulation of dust, or other foreign matter.

It is a still further object of the present invention to provide a bottle holding means which may be used with either a crate having a bottom, or a bottomless crate, and with either form of crate, the effectual closing of all grooves or crevices in the crate is maintained.

Various other objects of the present invention will appear as the description proceeds, and in describing the invention in detail, reference will be had to the accompanying drawings illustrating certain embodiments of the invention as the same has

been practised by me, though it is to be understood that while certain constructions are herein shown and described specifically, yet in the practice of the invention various changes may be made without departing from the general spirit of the invention.

In the drawings: Figure 1 is a perspective view of a bottle holding means embodying the features of the present invention, showing the same mounted in a crate, one of the sides of the latter being removed, and certain portions of the crate broken away to better illustrate features and advantages that will be hereinafter pointed out. Fig. 2 is longitudinal sectional view of the bottle holder constructed in accordance with the form shown in Fig. 1, a portion of the crate bottom being shown in this view in section, Fig. 3 is a transverse vertical sectional view of the same, Fig. 4 is a detailed view in elevation of a part of one of the side frame bars of the holder, and a part of one of the end walls of the crate, Fig. 5 is a detailed perspective view of a part of the two opposite side bars of the holder and one of the end bars thereof, Fig. 6 is a detached perspective view of one of the intermediate bars of the holder, Fig. 7 is a similar view of one of the upright spacing and stiffening members, Fig. 8 is a plan view of a bottle holding member constructed in accordance with my invention and adapted for use particularly with bottomless crates, Fig. 9 is a side elevation of the same. Fig. 10 is an end view thereof, Fig. 11 is a transverse vertical sectional view taken on the line 11—11 of Fig. 8, looking in the direction of the arrow, Fig. 12 is a longitudinal section view taken on the line 12—12 of Fig. 8 looking in the direction of the arrow. Fig. 13 is a detailed sectional view illustrating the manner in which the upright spacing and stiffening members are arranged, Fig. 14 is a detailed view in elevation of one of the intermediate bars of the holder, Fig. 15 is a detail view in side elevation of a part of one of the side bars showing a modified form of slot, and Fig. 16 is a similar view of one of the end bars used with the form of side bar shown in Fig. 15.

The invention in the present case resides in the particular manner in which the metallic bars from which the holder is con-

- structed are interwoven with each other and finally interengaged and firmly locked with each other to effect a rigid and unyielding bottle holder.
- 5 Referring to the construction of the device as embodied in Figs. 1 to 7 inclusive, the device is shown as comprising two spaced holding members disposed one above the other, and held in rigid spaced relation with respect to each other. The upper member which will be herein termed the upper holding member comprises a frame embodying two side bars 15 and two end bars 16. The lower holding member also comprises 15 two side bars designated 17 and two end bars 18. The side bars 15 are provided at equally distant spaced points with horizontally-extending key hole slots 19, the slots in the one side bar 15 matching with the 20 slots in the other side bar 15, that is, the slots 19 in both of these bars are equally spaced and are arranged in the same manner, the large ends of the slots in both bars extending in the same direction. The end bars 25 16 are provided with similar slots 20, and these slots in the two end bars 16 correspond to each other, in the same manner as the slots in the side bars 19 correspond to each other. The side bars 17 of the lower holding member are provided with like slots 19, and the end bars 18 of said lower holder also have similar slots. These slots in the respective bars of the lower holding member match in a similar manner to the slots 30 in the upper holding member bars.
- In Fig. 1 the holder is shown as mounted in the ordinary form of wooden shipping crate 21, and when used in connection with this form of crate, it is usual to groove the 40 side and end walls of the crate to receive the side and end bars of the holder in order to secure the latter in fixed position in the crate. This mounting of a metallic holder within a crate of this character is clearly 45 shown in Letters Patent No. 874,996 granted to me December 31, 1907, and in Letters Patent No. 899,010 granted to F. C. H. Haugk and myself September 15, 1908. In the latter patent referred to the grooves 50 are shown as extending but partially the length of the side and end walls, and in the first patent referred to the grooves are shown as extending the entire length of said walls. Objection has been made to each of 55 these forms owing to the fact that the grooves provide means for the accumulation of dust, dirt, and other foreign matter, which occasions trouble in maintaining the crate in a thoroughly clean condition. It is 60 of course advantageous in the manufacture to groove the walls throughout their length, since it is considerably less costly, but, besides the objection above noted, it has been found objectionable to extend grooves the 65 entire length of the walls on account of the

weakening thereof at the points where the grooves are made, and the danger of the walls splitting in case they are nailed together at the points where grooved. Another objection is the lack of stability in the 70 separating cells. The crimped or twisted wires for certain sizes have not enough resisting strength to hold their own in their partitions against pressure of heavy bottles when the crate is in an inclined position, and they will move from their intersecting points and let the bottles crush together, while any extra means of fastening is either expensive or unreliable.

In my invention I overcome all of the 80 above objections by constructing the holder of thin metal bars so interwoven and interlocked together as to give the necessary rigidity and strength and the side and end bars of each being of thin material and perfectly flat and rigid necessitating the providing of a groove only of sufficient size to neatly receive said side and end bars, the latter completely filling the grooves in the crate, and thus effect exclusion of dirt and 85 other foreign matter therefrom. This is fully illustrated and it is believed will be obvious from an inspection of Fig. 1, wherein the side bars and end bars of both the upper and lower holding members are shown 90 as neatly filling the grooves 22 provided therefor in the end and side walls of the crate 21. I preferably make the side bars 15, 17 greater in length than the intermediate bars to be hereinafter referred to, so as 95 100 to provide the ends 23 which overlap onto the ends of the end walls of the crate 21, thus closing up the ends of the grooves 22 in the side walls of the crate. This construction at the same time serves to securely fasten the frame in the crate and prevents 105 willful removal of the same.

As before stated, the holder is constructed from thin metallic bars, the side and end bars comprising the frame being flat, but the intermediate longitudinal and transverse interwoven and interlocked bars are preferably corrugated, as shown in Fig. 1, for the purpose of effectually holding the bottles spaced a sufficient distance from each other 110 to prevent contact. In the construction shown in Fig. 1 the upper holding member has a plurality of longitudinally-extending intermediate bars 24 and a plurality of interlocked transversely-extending bars 25 115 one series of the intermediate bars being interwoven with the other series of intermediate bars. Since these bars are the same in the upper and lower holding members, the same reference numerals will be applied 120 thereto. Each bar is of a form as shown in detail in Fig. 6, being notched in opposite side edges adjacent each end to form reduced necks defining T-shaped heads 26, and also provided throughout its length with equi- 125 130

distant notches 27 made in the edges of the bar and alternating or staggered in their arrangement in said edges.

In assembling the holder in accordance with the showing in Figs. 1 to 7, the end bars 16 or 18 are first engaged with the side bars 15 or 17 as the case may be to form the frame which receives the two series of intermediate bars. For clearness I will describe the assembling of the upper holder member, the assembling of the lower holder member being accomplished in similar manner. The end bars 16 are placed flatwise with respect to the side bars 15, the T-shaped heads are entered in the slots 19, and the end bars then given one quarter turn so as to interlock the T-shaped head 26 in the key hole slots 19, the enlarged ends of said slots forming bearings for the reduced necks when turning said end bars, the turning of the end bars being toward the enlarged ends of said slots. After the side and end bars have thus been interlocked together and the frame thus formed, the intermediate bars 24 have their T-shaped heads placed within the slots 20 of the end bars. These intermediate bars 24 are then given a one-quarter turn so as to bring the side faces thereof in a vertical position, the pressure it being remembered being directed toward the enlarged ends of the slots 20. The transversely-extending intermediate bars 25 are then placed in position by interweaving them with the longitudinally-extending bars 24. That is, each transverse bar 25 is placed over the top of one of the bars 24, underneath the succeeding bar 24 and on top of the next succeeding bar 24. These transverse bars 24 are so placed in this interweaving that the notches 27 thereof register with the similar notches in the bars 24. The heads 26 of the transverse bars are then engaged with the slots in the side bars. When thus engaged, these bars are given a one-quarter turn, the pressure thereon being directed toward the enlarged ends of the slots, and the bars snapped into interlocked engagement with the longitudinal bars 24. It will be noted that during this process of interengaging and interlocking the bars with each other, the frame will allow of the springing of the side bar so as to effect the entry of each transverse bar 25 up until the last bar 25 is inserted, and when this bar is placed in position the frame is effectually locked together and made perfectly rigid and inseparably joined.

For supporting the spaced members of the holder intermediate the ends thereof, I preferably employ uprights, one of which, as 28, is preferably placed directly at the center of the holder and the other two 29 of which may be placed at opposite sides of the central one 28 and disposed with their faces at right angles to the faces of the up-

right 28. Each upright is provided on a line intersecting with the plane of the lower frame with an opening 30 to receive the central intermediate bar 24 of the lower holding member, and the upper end of the upright is bifurcated as at 31 so as to form prongs which are bent over, as clearly illustrated in Fig. 1, and engaged with the central intermediate bar 24 of the upper holding member, the bifurcation in said upright receiving the central transverse intermediate bar of the upper holding member. The uprights 29 being placed with their faces at right angles to the faces of the upright 28, receive through the opening therein the central intermediate bar of the lower frame member, and have their upper ends receiving the central longitudinal intermediate bar of the upper holding member, and the prongs thereof engage with two of the transverse intermediate bars 25 of said upper frame member. These uprights are preferably shaped with their lower ends in a manner as shown at 32; so they may be engaged with the bottom 33 of the crate as clearly shown in Figs. 2 and 3, and thus assist in maintaining the rigidity of the bottle holding member. It will of course be understood that as many of these braces may be used as may be demanded by the size of the holding member.

In Figs. 8 to 14, the same broad conception of the manner of constructing the holding members of interlocking and interwoven bars is involved. In this construction, I have shown in addition to the bars forming the holder, a base or bottom for the bottle to rest upon. This construction is adapted for use with a bottomless crate, or in any connection where it is not desired to have the bottles rest upon the bottom of the crate in which the holder is arranged. This construction is particularly adapted for use in cases where, in addition to strength of the holding member, the utmost cleanliness is desired, as is the case for instance in crates used for milk bottles, which undergo a daily cleansing. The two holding members in this construction are identical with that above described, and the same reference numerals are therefore given thereto. The construction of the base 34 involves the same conception, in that it is made of side and end bars, and intermediate longitudinal and transverse interlocked and interwoven bars. These bars of the base are interlocked in the same manner as above described for the frames of the holder, though it will be obvious that a greater number of longitudinal or transverse intermediate bars will be necessary, in order to form a rest for the bottle. In the present illustration I have shown the longitudinal bars of the base as increased in number to those employed in the holding members. It will be readily

understood that where these bars are spaced only a short distance apart it will be difficult in the interweaving of the transverse and the longitudinal bars, to alternate with each bar, as, owing to the short space between the longitudinal bars, and the necessary closeness of the notches in the transverse bars, the latter would be liable to break at the notches. To obviate such risk and facilitate the work, I arrange the notches in these bars in the manner shown in detail for the bar designated 34^a in Fig. 14. In the construction illustrated, I have shown nine longitudinal bars in the base, and the notches are arranged in the opposite side edges of the transverse and longitudinal bars, so that the latter in assembling are passed either over or under three of the longitudinal bars, then under or over the three succeeding bars, and then over or under the last three bars. The stiffening and bracing uprights 35 shown in this construction connect the base firmly with the bottle holding members, these uprights receiving the central longitudinal bar of the upper and lower holder in the same manner as before described, and having their bifurcated ends clenched with the bars of the upper holding member and the bars of the base. It is preferable that these uprights 35 have their prongs ends clenched in opposite directions as clearly shown in Fig. 13, in which view the uprights are also shown as being interwoven with the bars of the holders.

The base in the construction above described is preferably formed entirely of flat uncrimped bars, and, since these bars are positioned with the wider faces vertically, their straight edges and cross-sections expose the least possible surface for retaining water, rust or dust. Such construction also permits of the base being easily cleansed as will be apparent.

In both constructions, I desire to call particular attention to the manner in which the bars are interlocked as has been set forth, particularly with respect to the fact that the pressure applied during the turning of the bar is always toward the enlarged ends of the slots which, as before stated, form bearings for the reduced necks of said bars. Such construction materially facilitates the rapid assembling of the holders as each bar as it is placed in position is not only firmly held, but the remainder of the holder is in such condition that the succeeding bars can be rapidly placed in position. In either construction, it is desirable and preferable to make all of the intermediate and transverse bars of both of the upper and lower holding member of corrugated outline, as such construction provides for the required spacing of the bottles, without necessitating the use of a heavy material for effecting this spacing. Consequently, the

holder may be constructed at a comparatively small cost, and while having the required strength and rigidity remains very light in weight which is a material desideratum in this class of devices.

I have herein shown and described the slots in the frame bars as having the enlarged portion of the opening at one end thereof, as this is the more practical construction, though I do not wish to confine myself to this particular form of opening, as obviously the interlocking of the bars may be effected by providing the enlarged portion of the slot intermediate the ends thereof, as in Figs. 15 and 16 wherein the slots 19^a are so shown. Obviously, also, the spacing of the slots may be equi-distant or otherwise spaced in each frame bar as the particular frame being constructed may require or demand. Attention is also called to the fact that in the construction shown and described, a device is built up of bars of the same width, and as a result, when the bars are interwoven and interlocked in the manner described, all of the bars lie in the same plane, the upper and lower edges of the intermediate and transverse bars being in a plane with the upper and lower edges respectively of the side and end bars, and the separating of the cells is uniform and fixed so as to resist pressure of any size bottle which they will receive.

I would have it understood that I claim broadly herein the particular manner of interlocking and interlacing the bars as herein shown and above described, and do not limit myself in this connection to the use of a frame so constructed.

What I claim is:—

1. A holding frame for crates including flat intersecting longitudinal and transverse bars arranged on edge, the outer longitudinal bars comprising the frame being provided with spaced longitudinal slots adapted to receive substantially T-shaped heads formed on the ends of the adjacent transverse bars, there being locking recesses formed in the upper and lower edges of the transverse and longitudinal bars and disposed at the intersection of said bars, said transverse bars being passed alternately over and under the longitudinal bars, whereby when the transverse bars are given a quarter turn, the recesses will interengage with the heads extending beyond the outer faces of the adjacent bars, thereby rigidly to lock all of said bars in a vertical plane.

2. The combination with a crate having a seating groove in the side and end walls thereof, of a holding frame supported with in said groove and including rigid intersecting longitudinal and transverse bars arranged on edge, the outer longitudinal bars being of greater length than the intermediate longitudinal bars and the terminals of

said outer bars interposed between the side and end walls of the crate at the junction thereof, said outer longitudinal bars being provided with key-hole slots, the enlarged 5 ends of which constitute bearings, there being similar key-hole slots formed in the outer transverse bars, the intermediate transverse bars being extended alternately over and under the edges of the intermediate 10 longitudinal bars and having locking recesses formed in their opposite edges and adapted to engage similar locking recesses formed in the opposite edges of the longitudinal bars, there being T-shaped heads 15 formed on the terminals of the transverse bars and terminals of the intermediate longitudinal bars and adapted to pass through the adjacent key-hole slots, whereby when the bars are given a quarter turn, the 20 recesses will interengage and the heads bear against the outer faces of the adjacent bars and lock all of said bars rigidly in a vertical plane.

3. A holding device for crates including

superposed frames, each comprising flat intersecting longitudinal and transverse rigid bars arranged on edge and having locking recesses formed in their opposite longitudinal edges and registering at the points of intersection of said bars, the transverse bars 25 of the frames being extended alternately over the upper edge of one longitudinal bar and under the under of the next adjacent longitudinal bar and having their opposite ends provided with substantially T-shaped 30 heads adapted to enter slots formed in the outer longitudinal bars, whereby when the transverse bars are given a quarter turn, the recesses will interengage and the heads bear 35 against the outer faces of the adjacent bars, 40 and a brace forming a rigid connection between said frames.

In testimony whereof I affix my signature in the presence of two witnesses.
